UNITED STATES PATENT OFFICE.

MARK S. MORSE, OF LOS ANGELES, CALIFORNIA, ASSIGNOR TO MAGNETIC SIGNAL CO.,
A CORPORATION OF CALIFORNIA.

BRAKE FOR WIGWAG SIGNALS.

Application filed January 25, 1923. Serial No. 615,421.

To all whom it may concern:

Be it known that I, MARK S. MORSE, a citizen of the United States, residing at Los Angeles, in the county of Los Angeles and State of California, have invented a new and useful Brake for Wigwag Signals, of which the following is a specification.

This invention relates to automatic traffic signal devices such as are employed at rail-way grade crossings for the purpose of warning traffic of the approach of a train or car.

A type of danger signal now extensively employed at grade crossings to notify traffic of the approach of a car or train has a wig-wag arm which is reciprocated back and forth to attract the attention of persons intending to cross the railway tracks, which arm is used in conjunction with audible means and other visible means such as a red light which is illuminated at the time the signal is in operation, so that the signal may be seen plainly at night.

The operating mechanism of a common form of such devices consists of an armature associated with the swinging arm which is alternately attracted in opposite directions by a pair of magnets. Being so magnetically operated, it is necessary that the bearings of such device be as near frictionless as possible, in order to keep down the power consumption thereof. This lack of friction in the bearings permits the wigwag arm to oscillate for some time after the device has been operated due to the passing of a car. The traffic, having become familiar with the fact that the wigwag arm continues to swing for a short time after a car has passed, has come to disregard the movement of this arm directly after a car has passed the crossing. The operation of the signal warning of the approach of a car closely following one which has just passed is often, for the above reason, disregarded, with the result of serious and sometimes fatal accidents.

It is the principal object of the invention to provide a wigwag signal which will abruptly cease the swinging of its wigwag arm when energization of the magnets is discontinued, thus making the giving of a false signal impossible.

The advantages of my invention and further objects thereof will be made evident hereinafter.

Referring to the drawing which is for illustrative purposes only:

Fig. 1 is a longitudinal vertically sectioned view showing the interior of a wigwag device equipped with a brake embodying the especial features of my invention, this section being taken substantially as indicated by the line 1—1 of Fig. 2.

Fig. 2 is a section taken substantially upon a plane represented by the line 2—2 of Fig. 1.

Fig. 3 is a fragmentary plan view taken upon a plane represented by the line 3—3 of Fig. 1, showing in plan the arrangement of the engaging arms and the stops mounted upon the brake band which is employed with the device.

As shown in Fig. 1 it is customary to mount the operating mechanism of a wigwag signal in a box 11 and to attach the wigwag arm 12 to the end of a shaft 14 which extends through the wall 15 of the housing 11. Upon the interior of the box 11 the shaft 14 has an armature 17 connected thereto, which is generally composed of a mass of iron. A pair of magnets 18 and 19 having windings 20 are mounted within the box 11 in angular positions relative to the vertical axis upon which the armature 17 hangs when not being actuated by the magnets. Upon the approach of a car or train, the magnets 18 and 19 are alternately energized by means of switch mechanism 22, located under a cover 23 situated within the box 11. The oscillation of the armature by the magnets causes the wigwag arm 12 to swing back and forth and also rings the bell 25 mounted upon the back of the box 11. And it is also customary to employ red lights, conspicuously mounted upon the signal, which are plainly visible at night.

The form of brake which I use with this wigwag signal to stop the oscillation of the wigwag after the car or train has passed, employs a sector casting 27 which is bolted upon the inner side of the front wall 15 of the box 11, in a position concentric with the

shaft 14. Upon this sector 27 a segment 5 brake band 28 is placed which is engaged at each of its ends 29 by a yoke 30 which has a tension spring 31 attached thereto, this tension spring being stressed by a screw 32 secured in the bottom of the box 11. Upon pins 34 and 35, each one of which is mounted centrally in an end of the armature 17, arms 37 are pivoted, to the ends of which arms 10 side bars 38 are secured by nuts 39. The forward ends 41 of the bars 38 extend over and rest upon the brake band 28, when the magnets 18 and 19 are not energized. The bars 38 being of iron serve as auxiliary armatures and are attracted and thus lifted by the magnets 18 and 19 whenever the device 15 is in operation, causing the arms 37 to swing upwardly upon the pivot pins 34 and 35 into engagement with stop pins 43 which prevent the arms 37 swinging to such a height 20 that the bars 38 would strike the extending cores 44 of the magnets.

From the foregoing, it will be perceived that whenever the device is in operation, the 25 arms 37 and the side bars 38 will be raised against the stop pins 43 by the magnetic flux flowing in the magnets 18 and 19. In such raised position the ends 41 of the side bars 38 clear and pass over engagement 30 lugs 46, mounted upon the brake band 28 at a slightly greater distance apart than the over-all width of the bars 38, so that the bars 38 may rest upon the brake band 28 between the engagement projections 46, 35 when the magnets are not energized.

The operation of the device is as follows: Through a suitable switch means the signal is supplied with current, upon the approach of a car, which current energizes the 40 magnets 18 and 19 alternately as previously described, causing the armature 17 to be attracted back and forth and thus oscillated as the magnetic flux is built up in either of the magnets. The bar 38 adjacent to the magnet being energized, is attracted upwardly so that as the armature 45 17 is pulled over, the ends 41 of the bars 38 will not engage the projection 46 adjacent thereto, but will ride freely thereover and permit the armature to pass through a complete oscillation. This attraction of the armature 17 and lifting of the arms 38 occurs alternately as the armature 17 is reciprocated in either direction, 50 and no interference of the action of the device is encountered due to the presence of the brake mechanism. Upon the discontinuance of the flow of current to the magnets, the arms 38 drop and the ends 41 55 thereof drop onto the brake band 28. If it happens that at the time of dropping of the arms 38, the armature 17 is drawn over considerably to one side so that one of the ends 41 drops outside the confines of the 60 two engagement members 46, the end 41

rides over the sloping face of whichever of the members 46 is adjacent thereto, and is thus brought within the confines of the members. Then as the armature swings over, due to the oscillating tendency of the 70 target attached to the arm 12, one of the ends 41 of the bars 38 engages an engagement member 46 and causes the brake band 28 to slide upon the sector 27 against the centralizing action of the spring 31, and as the armature is then swung in the opposite direction, the opposite end 41 comes into contact with an engagement member 46 and the brake band 28 is forced in the opposite direction upon the sector 27. The 75 brake band 28 is frictionally disposed upon the segment 27 and acts in combination with the centralizing spring 31 to bring the wigwag arm 12 quickly to rest, immediately 80 upon the shutting off of the current to the signalling device.

Nearly all wigwag signals employ electro-magnetic action in their operation. From the foregoing description it will be understood that my invention includes broadly the idea of employing a brake with any magnetically operated wigwag device, which brake is ordinarily active but becomes inactive, so as to cause no interference with the action of the signal, when a current is flowing through the operating elements of the signal device.

I claim as my invention:

1. In a traffic signal, the combination of: 100 an armature; electro-magnets for reciprocating said armature; a brake member; a connector for transferring the reciprocation of said armature to said brake member, whereby said brake member will normally inhibit movement of said armature; and auxiliary armature means associated with said connector and adapted to be attracted by the magnetic flux induced by current flow through said electro-magnets, to permit movement of said armature when said electro-magnets are energized.

2. A combination, as in claim 1, in which 105 said connector is movably secured upon said armature and engages said brake member.

3. In a traffic signal, the combination of: 110 an armature; electro-magnetic means for translating said armature; a swinging arm; a brake member independent of said swinging arm; and a connector for transferring movement of the armature to said brake member, said connector being rendered inoperative by the magnetic flux induced in said electro-magnetic means by the flow of current therethrough.

4. In a traffic signal, the combination of: 115 an armature; electro-magnets for reciprocating said armature; a sector mounted concentric with said armature; a brake band upon said sector; a pair of bars pivotally 120

mounted upon said armature, the ends of said bars normally resting upon said brake band and adapted to be raised therefrom by the magnetic attraction of said electro-
5 magnets; and projections upon said brake member for limiting the relative movement between said bars and said brake band

when said bars are resting upon said brake band.

In testimony whereof, I have hereunto set my hand at Los Angeles, California, this 7th day of October, 1922.

MARK S. MORSE.
